(57) **CLAIM**

The ornamental design for the rotary torque transfer unit for photo-sensitive drum of image forming apparatus, as shown and described.

DESCRIPTION

FIG. 1 is a perspective view of a rotary torque transfer unit showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an enlarged perspective view of the front end portion thereof;

FIG. 9 is an enlarged, cross-section view thereof, taken along line 9-9 of FIG. 8;

FIG. 10 is an enlarged, cross-section view thereof, taken along line 10-10 of FIG. 8;

FIG. 11 is a perspective view thereof, showing the rotary torque transfer unit aligned for connection with a gear element;

FIG. 12 is a side view thereof, showing the connection of the rotary torque transfer unit to a cross-sectioned portion of a gear element; and,

FIG. 13 is a perspective view of the back end thereof. The broken lines depict environmental subject matter only and form no part of the claimed design.
